LOCK SEAMED SPUD

Harold Millard Sheridan, New Boston, Ohio, assignor to American Flange & Manufacturing Co. Inc., New York, N. Y., a corporation of Illinois

Application January 12, 1937, Serial No. 120,316

2 Claims. (Cl. 285—49)

The invention relates to a spud construction and more especially to a lock seamed spud.

The primary object of the invention is the provision of a spud of this character, wherein 5 through the construction thereof the same can be placed in the opening of a metal tank and lock seamed therewith in a manner that the spud can not be knocked out, turned and will be positively leakproof.

10 Another object of the invention is the provision of a spud of this character, wherein either a plug or a cap can be fastened in place for the sealing of the opening accommodating the spud.

A further object of the invention is the provision of a spud of this character, which is simple in construction, susceptible of being lock seamed with a tank so as to render the seam leakproof, strong, sturdy, neat in appearance, and inexpensive to manufacture and install.

20 With these and other objects in view, the invention consists in the features of construction, combination and arrangement of parts as will be hereinafter more fully described, illustrated in the accompanying drawing, which discloses the 25 preferred embodiment of the invention and pointed out in the claims hereunto appended.

In the accompanying drawing:

Figure 1 is a top plan view of a capped spud constructed in accordance with the invention and 30 lock seamed with the body of a tank.

Figure 2 is an enlarged sectional view on the line 2—2 of Figure 1 looking in the direction of the arrows.

Figure 3 is a fragmentary sectional view similar 35 to Figure 2 showing the spud in position prior to lock seaming the same with the tank.

Figure 4 is a view similar to Figure 1 with the cap removed.

Figure 5 is a view similar to Figure 3 showing 40 the spud when initially inserted in the hole or opening in the tank.

Figure 6 is a fragmentary sectional view similar to Figure 2 showing a modification with a plug inserted in the spud.

45 Figure 7 is a fragmentary vertical sectional view showing a modified form of spud.

Figure 8 is a view similar to Figure 7 showing a further modification of spud.

Similar reference characters indicate corresponding parts throughout the several views in the drawing.

Referring to the drawing in detail, particularly Figures 1 to 5 inclusive, A designates generally a portion of a metal tank having a suitable opening for the filling of such tank or the

discharging of its contents and mounted in this opening is the spud B constituting the present invention and hereinafter fully described.

The spud B comprises an annular or ring-like body 10 made from metal and of a height sufficient for a required number of threads 11 both internally and externally thereof for the fitting of a cap 12 thereon. This cap 12 carries a sealing gasket 13 which rides the top of the body 10 and is confined within a seat 14 within the cap 10 between an outer peripheral rim 15 and the center body portion 16 thereof so that when the cap is screwed home a fluid-tight closure will be had for the opening in the tank A.

The body 10 of the spud B is formed with an 18 external annular outstruck flange 17 for seating within a countersunk recess 18 formed by an in-bent circular shoulder 19 instruck from the edge of the opening in the tank A. The flange 17 in its bottom face is formed with an annular 20 channel 20 for a packing ring 21 which has contact with the shoulder 19 to effect a leakproof joint between the flange and said shoulder.

The body 10 below the flange 17 is formed with a depending circular shaped bendable skirt or a 25 relatively thin bendable annulus 22 constituting an extension of the body while augmenting the shoulder 19 is an annular seaming extension 23 which is of considerably less extent than the annulus 22 so that the latter can be folded over 30 the said extension 23 and thence the folded over portion of the annulus 22 and the extension 23 bent outwardly and upwardly against the under side of the shoulder 19 thereby effecting a lock seamed connection between the spud B and the 35 tank A as will be clearly apparent from Figure 2 of the drawing.

This lock seaming of the spud on the tank A will effect a leakproof joint therebetween at the opening in the tank A and also will prevent the 40 spud from being knocked out or turned or otherwise accidentally separated from the tank.

Within the hollow head of cap 12 are upstanding spanner wrench lugs, shown at 27. These may be engaged by any suitable spanner wrench 45 or similar tool for tightening down or removing the cap.

In Figure 6 of the drawing the spud C, which is identical to the spud B, has threaded therein a closure or sealing plug 28 which is internally 50 threaded to the spud. This plug has a laterally extending flange 28a underneath which is carried a gasket 28b. This gasket seals the opening by being pressed between flange 28a and the top face of spud C.

In Figure 7 of the drawing there is shown a slight modification of spud wherein the lock seaming of the body 29 of such spud with the tank 30 is identical to that hereinbefore set forth 5 while this body of the spud 29 is turned outwardly and downwardly on itself at 31 and is internally screw threaded at 32. The outwardly and downwardly turned portion 31 of the body 29 has contact with a sealing gasket 33.

10 A still further modification is shown in Fig. 8 of the drawing wherein the body portion of the spud is shown as thickened at 34 and as having the lower part of the thickened portion received within the countersunk seat around the opening 15 in the container or tank A. The bottom surface of this thickened portion is shown as formed with a gasket receiving recess or depression 35, between which and the shoulder of the countersunk seat is received a sealing gasket 36. In this construction also, the portion of the spud, which is 20 lock-seamed with the container wall, extends directly down in line with the root of the internal threads 37. By employing this latter expedient as well as providing the thickened portion 34 in 25 place of flange 17, as shown in the form of Figs. 1 to 6, a somewhat more compact construction is provided.

It is, of course, understood that the invention before described is not limited to a complete 30 double seaming of the spud and stock because it is contemplated, if found necessary, to form mutilations in the seaming at determined intervals thereof for the better draining of the contents of a container and also to better secure the 35 spud. This mutilation may be effected at one or more places in the seaming of the stock and be thus effected by having the turned portion of the body shorter than the seaming skirt of the spud so that when the spud and body stock are 40 seamed together there will be cut out places in the spud and stock.

The bendable skirt 22 of the spud can be bent outwardly and upwardly against the under side of the shoulder 19 without the presence of the extension 23 or this extension may be made the same length as the skirt 22 of the spud. Furthermore, corrugations at intervals around the seaming may be formed, this being effected by a tool active on the extension and the skirt when together. 5

By eliminating the skirt 22 from the spud the 10 latter can be used as an electric or acetylene welded enclosure.

It is contemplated to thread the spud internally and also that said spud be made by turning the steel outwardly and downwardly to form a 15 shoulder with one or more cut-out portions to give such shoulder an uneven line and thus producing a countersunk seat and in this manner the spud occupying the countersunk seat will be 20 kept from turning.

What is claimed is:

1. In structure of the class described, a container wall having an opening therein with a countersunk seat therearound and a neck extending from said seat, a spud having a portion embraced by said countersunk seat and a portion extending from said embraced portion, said 25 extending portion and said neck being interlocked and folded over to form a joint underlying and reinforcing said countersunk seat. 30

2. In structure of the class described, a container wall having an opening therein with a countersunk seat therearound and a neck extending from said seat, a spud having a returned bent portion embraced by said countersunk seat 35 and a portion extending from said embraced portion, said extending portion and said neck being interlocked and folded over to form a joint underlying and reinforcing said countersunk seat.

HAROLD MILLARD SHERIDAN. 40
